UNITED STATES PATENT OFFICE.

ROBERT E. SCHIEBER, OF DETROIT, MICHIGAN, ASSIGNOR TO THE CENTRAL STAMPING CO., OF DETROIT, MICHIGAN, A CORPORATION OF MICHIGAN.

PUSH BUTTON.

Application filed September 19, 1921. Serial No. 501,522.

To all whom it may concern:

Be it known that I, ROBERT E. SCHIEBER, a citizen of Germany, residing at Detroit, in the county of Wayne and State of Michigan, 5 have invented certain new and useful Improvements in Push Buttons, of which the following is a specification, reference being had therein to the accompanying drawings.

In my pending application Serial No. 10 487,346, filed July 25, 1921, there is disclosed a push button construction that may be advantageously used on the steering column of an automobile or other vehicle for electrically operating audible and visible signals 15 or other electrically controlled devices.

This invention relates to a somewhat similar push button and aims to simplify the construction of my prior application and at the same time retain certain novel features 20 thereof.

The construction of my improved button will be hereinafter described and then claimed, and reference will now be had to the drawing wherein,

25 Figure 1 is a vertical cross sectional view of the push button;

Fig. 2 is a vertical transverse sectional view of the same;

Fig. 3 is a plan of the push button with 30 the cap thereof removed to show the resilient contact member;

Fig. 4 is a similar view of the base or nut of the push button, and

Fig. 5 is a side elevation of the push button, partly broken away and partly in section, showing the manner of mounting the cap on the base or nut of the push button.

To put my invention into practice, I provide a nut 1 with a cylindrical collar 2 having 40 a peripheral flange 3 disposed in parallelism with one end of the nut 1 so as to form an annular groove 4. At one side of the nut there is a groove or passage 5 which intersects the collar 2 and the flange 3 so as 45 to provide clearance for wires or conductors 6.

Detachably mounted on the collar 2 and the flange 3 thereof is a disk 7 of insulation material, as fiber, and the central portion of the 50 fiber disk is provided with rivets 8 and 9 to which the wires 6 are connected, said disk having a recess 10 at the passage 5 of the nut 1 providing clearance for the wires 6.

The head of the rivet 8 serves as a stationary contact member and the rivet 9 is employed

for holding a resilient contact member 11 which overlies the rivet 9 and is adapted to be depressed to engage the rivet 8 and complete an electric circuit. The resilient contact member 11 is in the form of a strip of 60 metal bent to provide an apex portion by which the contact member may be depressed.

Detachably mounted over the disk 7 and the connections carried thereby is a sleeve 12 having its outer end provided with an 65 inturned flange 13 to overlie a peripheral flange 14 carried by a cylindrical button member 15 slidable in the sleeve 12. The button 15 is made of fiber or other insulation material and the flat inner face of the 70 button engages the apex of the resilient contact member 11, so that pressure on the button 15 will depress the resilient contact member 11 and cause it to engage the stationary contact member 8 and thus connect 75 the wires 6 for an electric circuit. The button 15 is limited in its outward movement by the inturned flange 13 of the sleeve 12 and by reason of the resilient contact member 11 being made from a wide strip of 80 metal the button 15 is substantially supported within the sleeve 12 and cannot accidentally tilt therein or become accidentally displaced.

Retaining the sleeve 12 in engagement 85 with the nut are opposed indented portions or teats 16 at the inner end of the sleeve 12, as best shown in Fig. 5, and by tilting the sleeve 12 first one teat can be placed under the flange 3 and then the other teat, providing the teat is placed at the wires 6 and the sleeve 12 partially rotated when said sleeve is shifted towards the nut 1. This operation 90 will carry both of the teats into the groove 4 and the sleeve 12 will be held, as shown in 95 Fig. 2.

The expansive force of the resilient contact member 11 will retain the flange 14 of the button 15 in engagement with the flange 13 of the sleeve 12 and the teats 16 of said 100 sleeve in engagement with the flange 3, so that all parts of the button construction are assembled against accidental displacement, yet permitting of the parts being separated for any purpose.

The nut 1 has the usual bore with its walls screwthreaded so that the nut may be mounted on the upper end of a steering column or post or attached to any screwthreaded support.

One embodiment of my invention has been illustrated, but it is to be understood that the structural elements are susceptible to such changes as fall within the scope of the appended claim.

What I claim is:—

A push button comprising a nut, a disk on said nut, rivets attached to said disk and holding lead-in wires, a resilient contact member held by one of said rivets and adapted to be depressed to engage the other rivet, and means attached to said nut and en-

closing said disk and contact member and adapted to facilitate depressing said contact member, it being necessary to tilt and rotate said means for attachment to said nut.

In testimony whereof I affix my signature in presence of two witnesses.

ROBERT E. SCHIEBER.

Witnesses:
